UNITED STATES PATENT OFFICE.

LOUIS G. PACENT, OF WINFIELD, NEW YORK.

DESIGN FOR A TELEPHONE RECEIVER.

Application filed January 11, 1924. Serial No. 8,293. Term of patent 14 years.

To all whom it may concern:

Be it known that I, LOUIS G. PACENT, a citizen of the United States, residing at Winfield, Queens County, Long Island, New York, have invented a new, original, and ornamental Design for Telephone Receiver, of which the following is a specification, reference being had to the accompanying drawing, forming part thereof.

Figure 1 is a side view of a receiver built in accordance with my new design; Figure 2 is a back view of the same; and Figure 3 is a view in perspective.

I claim:

The ornamental design for a telephone receiver as shown.

LOUIS G. PACENT.
